UNITED STATES PATENT OFFICE.

GEORG SCHOENNER, OF NUEREMBERG, GERMANY.

COMPASSES.

SPECIFICATION forming part of Letters Patent No. 755,395, dated March 22, 1904.

Application filed November 7, 1903. Serial No. 180,256. (No model.)

To all whom it may concern:

Be it known that I, GEORG SCHOENNER, manufacturer, a subject of the Emperor of Germany, and a resident of Nuremberg, in the Empire of Germany, (whose post-office address is 7 Gartenstrasse, Nuremberg aforesaid,) have invented certain new and useful Improvements in Compasses, of which the following is a specification.

10 This invention has for its object a pair of compasses having an insertion-piece, in which compasses, by means of a very simple improved arrangement, not only is the insertion held fast and its adjustment as regards direction, (or rather its security against displacement,) but also a fine adjustment of the width of the compasses is obtained. In order to obtain these advantages, there is arranged on the inner side of the leg of the compasses,

15 which leg serves for receiving the insertion-piece, a spring-tongue, (a strip spring held fast at one end,) which closes the aperture for the insertion of the piece in the compass-leg.

In the accompanying drawings, Figure 1 is an elevation of a pair of compasses fitted with this improved arrangement, and Fig. 2 a similar view of a modification; while Fig. 3 is a vertical section and partial elevation, on an enlarged scale, of the insertion-piece; and Fig.

20 4, a detail view.

A pin *b*, provided in the ordinary manner on an insertion-piece *a*, is beveled off at the side, which when the insertion is in use faces the middle of the compasses. The compass-leg *c* has at its lower end a recess *d*, opening downward and toward the middle of the compasses, in which recess *d* a strip-spring *e*, forming a tongue, lies entirely or partially countersunk and is held at one side by means of a small screw *f*. After the insertion-pin *b* has been introduced into the insertion-aperture remaining behind the spring-tongue *e* the tongue *e* in consequence of its elasticity bears against the beveled side of the pin *b*, so that

25 the insertion is retained in its position and direction by being clamped and secured against

being turned without its being necessary to provide a separate pressure or clamp screw for this object. On the outside of the compass-leg a pressure-screw *g* is arranged and 50 serves exclusively for effecting the fine adjustment of the compasses. If, in fact, the rough adjustment of the compasses has taken place in the ordinary manner and the screw *g* be screwed in the direction toward the middle of the compasses, it presses the insertion-pin *b* against the spring-tongue *e*, whereby the free end of the latter is bent toward the middle of the compasses. As the upper end of the insertion-pin remains at its original 60 place, (see Fig. 2,) the entire insertion turns a little on this point. It is thus possible to obtain any desired fine adjustment of the compasses.

I declare that what I claim is—

1. A pair of compasses having one of the legs thereof provided with a groove or elongated aperture in its inner face extending to the end of said leg, an insertion-piece adapted to fit said leg, and a spring closing the entire open 65 side of said opening and bearing against the side of the insertion-piece and a set-screw extending through the opposite wall of said leg for swinging the insertion-piece against the tension of the spring substantially as described.

2. In a pair of compasses an insertion-piece such as described, a spring *e* bearing against one side of the insertion-piece, a screw *g* arranged opposite the spring *e* on the leg *c* of 80 the compasses and adapted to move said insertion-piece *a* toward the middle of the compasses against the resistance of the spring *e*, and in this manner to operate a fine adjustment of the width of the compasses, substantially as set forth.

In witness whereof I have hereunto set my hand in presence of two witnesses.

GEORG SCHOENNER.
